UNITED STATES PATENT OFFICE.

WILLIAM J. CUSSEN, OF RICHMOND, VIRGINIA, ASSIGNOR OF TWO-THIRDS
TO M. MILLHISER & CO.

TOBACCO-BAG.

SPECIFICATION forming part of Letters Patent No. 361,619, dated April 19, 1887.

Application filed September 10, 1886. Serial No. 213,213. (Model.)

To all whom it may concern:

Be it known that I, WILLIAM J. CUSSEN, a citizen of the United States, residing at Richmond, in the county of Henrico and State of 5 Virginia, have invented certain new and useful Improvements in Tobacco-Bags, of which the following is a specification, reference being had therein to the accompanying drawings.

This invention relates to certain improvements in bags for tobacco or other articles which in a prime condition contain, necessarily, a certain amount of moisture; and it has for its object to provide a bag for the tobacco or other article constituting the original 15 package which will retain such moisture and prevent the article from drying before as well as after the package has been opened.

To this end my invention consists in a double bag, or a bag having an internal lining, the 20 interior bag or lining being chemically prepared to retain the original moisture of the tobacco or other article, and by preventing evaporation keep the same always in prime condition, the outer bag serving for ornamentation, as well as to further retain the moisture.

In the drawings, Figure 1 represents a perspective view of a bag constructed according to my invention, showing a portion of the outer part cut and turned back, so as to expose the 30 inner portion or lining, and Fig. 2 a transverse sectional view of the bag.

The letter A indicates the outer bag, which is constructed of any suitable material, and B the inner bag, which is constructed of textile 35 or other fabric chemically or otherwise prepared to retain the moisture of the contained

article. The bag at its edges is provided with the usual draw-strings, by means of which it may be opened or closed.

In preparing the inner bag or lining, which 40 is a textile fabric, I prefer to saturate it with glycerine, but do not limit myself to such, as other substances capable of absorbing and retaining moisture may be used for the purpose.

I am aware that bags and pouches for tobacco, having an interior bag or lining of various materials, have been employed heretofore. The inner linings of such bags, however, have never been prepared so as to form the original 50 package to receive and retain the tobacco in prime condition, as they would not withstand the pressure necessary for the packing, and in most instances would impart a disagreeable flavor to the tobacco, such bags being mainly 55 intended as receptacles to carry the tobacco about the person.

Having thus described my invention, what I claim, and desire to secure by Letters Patent, is—

A bag for tobacco and other material which is moist when in prime condition, consisting of an internal bag of textile fabric chemically prepared to retain moisture as well after as before the bag is opened and an external in- 65 closing-bag, substantially as specified.

In testimony whereof I affix my signature in presence of two witnesses.

WILLIAM J. CUSSEN.
